UNITED STATES PATENT OFFICE.

LATIMER H. BALLOU, OF LAWRENCE, MASSACHUSETTS.

WINDING-ARBOR.

1,179,265.

Specification of Letters Patent. Patented Apr. 11, 1916.

Application filed December 30, 1915. Serial No. 69,386.

To all whom it may concern:

Be it known that I, LATIMER H. BALLOU, a citizen of the United States, residing at Lawrence, in the county of Essex and State 5 of Massachusetts, have invented certain new and useful Improvements in Winding-Arbors; and I do hereby declare the following to be a full, clear, and exact description of the invention, such as will enable others 10 skilled in the art to which it appertains to make and use the same.

The invention relates to winding arbors for cloth winding machines.

The object of the invention is to provide 15 a novel and improved construction of winding arbor upon which cloth may be wound without the production of longitudinally extending wrinkles in the initial convolutions of the roll, and which may be readily 20 removed from the finished roll.

To this end the invention comprises the 25 features of construction and combinations of parts hereinafter described and referred to in the claims, the advantages of which 30 will be apparent to those skilled in the art from the following detailed description of the preferred form of the invention.

The invention will be readily understood 35 from an inspection of the accompanying 40 drawings and the following detailed description of the mechanism illustrated therein.

In the drawings, Figure 1 is an elevation 45 showing so much of a cloth winding machine as is necessary to illustrate the application of the present invention thereto; Fig. 2 is a detailed sectional view showing the left-hand end of the arbor and its supporting socket; Fig. 3 is a sectional elevation showing the right-hand end of the arbor and its supporting socket; Fig. 4 is a 50 sectional view on line 4—4, Fig. 2; Fig. 5 is a sectional view on line 5—5, Fig. 3; and Fig. 6 is a detailed view of the right-hand end of the arbor.

In the drawings the invention is shown 55 as applied to a cloth winding machine such as is commonly used for winding cloth into rolls or bales for shipment. This machine 60 comprises a fixed winding shaft 2 and an opposed longitudinally movable winding shaft 4 which during the winding are driven in unison through gears 6 and 8. The fixed shaft 2 is held from longitudinal movement 65 in its bearings by the collars 10, while the shaft 4 is provided with a grooved collar

12 adapted to be engaged by the forked end of a lever (not shown) by which the shaft may be moved longitudinally as occasion requires. The gear 8 is keyed to the 60 shaft 4 so that it will drive the shaft while permitting it to be moved longitudinally.

The winding arbor shown, which embodies the preferred form of the invention, is adapted to be applied to the machine 65 above described, and comprises two oppositely tapered unconnected bars 14 and 16, and two sockets 18 and 20 which are constructed to receive the ends of the bars and hold them in winding relation. Each of the 70 bars 14 and 16 is provided with a slot 22 extending from its thin end nearly to its opposite end. These slots register with each other and form a cloth receiving slot extending through the arbor when the bars 75 are assembled and held together by the sockets 18 and 20. The recesses within the sockets are shaped to fit the ends of the assembled bars, and are preferably provided with spurs 24 which project into the open 80 ends of the slots 22 and maintain the sides of the bars in substantial alinement with each other when subjected to the pressure of the cloth which is being wound thereon.

The fixed shaft 2 of winding machines 85 as usually constructed is provided at its end with a plate 26, and the holding socket 18 of the arbor is therefore preferably made in the form of a recessed plate, and is provided with screw holes adapted to register 90 with the screw holes of the plate 26, and to receive the screws 28 by which the socket is secured to the plate. The socket 20 is preferably in the form of a recessed collar adapted to fit over the end of the longitudinally movable shaft 4, and is secured thereto 95 by a set screw 30.

To insert the bars 14 and 16 of the arbor in the machine, the shaft 40 is withdrawn, and the thin slotted end of the bar 14 and 100 the unslotted thick end of the bar 16 are inserted in the socket 18, after which the shaft 4 is advanced to engage the socket 20 with the slotted end of the bar 16 and unslotted end of the bar 14. The bars of the 105 arbor are thus secured in assembled position with the tapered faces of the bars in engagement, and with the slots 20 in alinement and forming a cloth receiving slot which extends through the cloth supporting 110 part of the arbor. This slot extends parallel to the surface and peripheral edges of

the arbor, so that the cloth may be drawn smoothly and uniformly about the arbor as the initial convolutions are wound thereon. This avoids the formation of folds or wrinkles extending transversely of the cloth and longitudinally of the arbor, such as are formed in winding the initial convolutions about an arbor having a cloth receiving slot which is inclined or at an angle to the surface of the arbor, as in the construction of arbor shown and described in applicant's prior Patent No. 983,600. While the cloth receiving slot is parallel to the cloth supporting surface of the arbor, the bars of the arbor may be readily removed without disturbing the inner end of the cloth by reason of the oppositely tapered form of the bars, and the provision of the open-ended slots extending through the thin ends of the bars. The bar 14 may be provided with a cross-piece 32 to assist in withdrawing the bar.

While it is preferred to employ the specific construction and arrangement of parts shown and described, in embodying the invention in an arbor construction which may be readily applied to existing winding machines, it will be understood that this con-

struction and arrangement are not essential to the broader features of the invention, but may be varied or modified without departing therefrom.

Having explained the nature and object of the invention, and specifically described one form of mechanism in which it may be embodied, what is claimed is:—

1. A winding arbor for cloth winding machines comprising a pair of unconnected oppositely tapered bars, each of which is slotted from its thin end nearly to its opposite end, and sockets within which the ends of the assembled bars fit adapted to be secured to the opposed ends of the winding shafts of a winding machine.

2. A winding arbor for cloth winding machines comprising a pair of unconnected oppositely tapered bars, each of which is slotted from its thin end nearly to its opposite end, and sockets for the ends of the assembled bars provided with spurs entering the open ends of the slots and adapted to be secured to the opposed ends of the winding shafts of a winding machine.

LATIMER H. BALLOU.
